HIGHWAY DANGER SIGNAL DEVICE

Doctor James Parris, Gaffney, S. C.

Application April 1, 1940, Serial No. 327,349

2 Claims. (Cl. 200—86)

The invention relates to a treadle switch controlled traffic signaling system and more especially to highway danger signal devices.

The primary object of the invention is the provision of a system or device of this character wherein either visible or audible signals may be had for regulating traffic, particularly at street intersections, side roads, bridges, school zones, curves, deadend streets and other places where safety against accidents must be had and required.

Another object of the invention is the provision of a system or device of this character wherein the signals are under the control of treadles, a pair being installed, and are operated by the weight of vehicles so that a signal will be given and shut off at the proper interval for safety to the traffic using highways, roads or other traveled courses, the system or device being equally applicable for the control of 20 pedestrian or vehicular traffic.

A further object of the invention is the provision of a system or device of this character wherein the traffic traveling in opposite or reverse directions to each other will effect the 25 automatic working of signals so that the traffic can be assured of safety in the travel thereof, particularly where caution and safety is required and in this way avoiding congestion, especially at intersections.

A still further object of the invention is the provision of a system or device of this character, which is extremely simple in its construction, susceptible of being installed in a ready and easy manner and with dispatch, being devoid of a 30 number of complicated parts, thoroughly reliable and efficient in operation, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention and pointed out in the claims hereunto appended.

In the accompanying drawing:

Figure 1 is a diagrammatic plan view fragmentarily disclosing an intersection of traffic ways showing the system or device constructed in accordance with the invention installed.

Figure 2 is an enlarged sectional view taken on the line 2—2 of Figure 1 looking in the direction of the arrows.

Figure 3 is a bottom plan view of one of the

treadle setups employed in the system or device.

Figure 4 is a sectional view taken on the line 4—4 of Figure 2 looking in the direction of the arrows.

Figure 5 is a sectional view taken on the line 5—5 of Figure 1 looking in the direction of the arrows.

Figure 6 is a bottom plan view of Figure 5.

Figure 7 is a sectional view taken on the line 7—7 of Figure 5 looking in the direction of the arrows.

Figure 8 is a sectional view on the plane indicated by the line 8—8 of Figure 5 with the treadle up and the contacts 15 and 16 separated.

Figure 9 is a sectional view similar to Figure 8 but with the treadle down and the contacts 15 and 16 in engagement.

Similar reference characters indicate corresponding parts throughout the several views in the drawing.

Referring to the drawing in detail, A designates generally a portion of a road, which is intersected by another road B, and at such intersection are erected in this instance visible, electrically operated signals C, each being of any selected or preferred detailed construction and are mounted in any suitable manner to be visible to traffic traveling toward the road A from the road B in opposite directions along the latter.

Of course, the signal C may be of audible type and in this instance there is but a pair arranged at the intersection visible only to the traffic on the road B although additional signal equipment can be for the road A controlled and operated by the traffic on the road B.

The signals C are operated and controlled by traffic on the road A, one being operated and controlled by the traffic flowing in one direction and the other signal for the traffic flowing 40 in the reverse direction.

Each signal C is adapted to be operated by a switch treadle 10 of substantially elongated formation disposed transversely of the road A at the required distance removed from the intersection of the road B therein. The treadle 10 is pivoted at 11 for vertical swinging movement in a hanger 12 integrally formed within a boxing or housing 13 which is countersunk in the road bed. This treadle at the under side thereof is equipped with an insulating block 14 carrying a switch contact 15 while the boxing or housing adjacent to this block 14 is equipped with a swingable switch contact 16. This switch contact 16 is insulated by the swingable member 17 for the contact 16. This member 17 is pivoted

at 18. The member 17 is acted upon by a coiled retractile spring 19 fixed to the treadle 10 at the under side thereof so as to urge the contact 16 into engagement with the contact 15 and also to have the member 17 latch with the block 14 to hold the treadle 10 depressed. The treadle 10 is supported upon a compression spring 20, which normally maintains it elevated and the contacts 15 and 16 out of engagement with each other when the said treadle is in its normal elevated position.

The switch contacts 15 and 16 are included in an electric circuit 21 having the signals C arranged therein. When the contacts 15 and 16 engage with each other, the signals C will be rendered visible or illuminated and when the switch contacts are separated the signals C are shut off.

Approximately at the center of the intersection of the roads A and B are arranged treadles 22, each being common to one of the treadles 10, and such treadle 22 is vertically swingable on a pivot 23 within a housing or box 24 embedded in the road's intersection bed. The treadle 22 is elevated by a compression spring 25 and when the said treadle is depressed, it operates a bell crank lever 26 pivoted at 27. One of the arms, that is, the arm 28 of the bell crank lever has flexible connection 29 with the swingable member 14 so that when the said treadle 22 has been lowered by the weight of a vehicle thereon the member 14 will be caused to unlatch the treadle 10 previously depressed by the vehicle and concurrently therewith the switch including the contacts 15 and 16 will come open thus shutting off the signal when the vehicle has reached a point well within the intersection of the roads A and B. In this manner safety will be assured at the intersection to avoid the entrance of vehicular traffic to the crossing or intersection of such road B with the road A.

The treadle 10 is for rendering the signal C active for signaling purposes while the treadle 22 is to render the same inactive.

By reason of the disposition of the treadle 10, the signal C will be operated well in advance of the vehicle entering the intersection of the roads A and B or such vehicle reaching a danger point of travel thereof.

The signals C are automatically controlled and the on-and-off operation thereof is had by the working of the treadles 10 and 22, respectively, these being susceptible of becoming depressed by the weight of vehicles traveling thereover.

What is claimed is:

1. A treadle switch, comprising a casing having an opening in its upper end, a treadle pivoted within the opening adjacent one end, spring means below the opposite end of the treadle for holding the same slightly above the casing, a contact member carried by the lower face of the treadle adjacent its free end, a swinging combined latch and contact carried by the casing and adapted to engage the first mentioned contact for completing a circuit and holding the treadle down in a plane with the upper end of the casing, and means for moving the swinging latch and contact out of engagement with the other contact.

2. A treadle, comprising a casing having an opening in its upper end, a treadle pivoted at one end within the opening, spring means below the opposite end of the treadle for holding the same slightly above the casing, a contact member carried by the lower face of the treadle adjacent its free end and spaced a slight distance from the treadle, a swinging combined latch and contact carried by the casing and normally inwardly spring held and adapted to pass beneath the contact carried by the treadle for completing a circuit and holding the treadle down in a plane with the upper end of the casing, and means for moving the swinging latch and contact out of engagement with the other contact.

DOCTOR J. PARRIS.
